UNITED STATES PATENT OFFICE.

CARL SCHÜRMANN, OF DUSSELDORF, GERMANY.

ROLL-CALENDER.

1,257,746.

Specification of Letters Patent. Patented Feb. 26, 1918.

Application filed March 25, 1916. Serial No. 86,556.

To all whom it may concern:

Be it known that I, CARL SCHÜRMANN, a citizen of the Empire of Germany, and a resident of 27 Winkelsfelderstrasse, Dusseldorf, Germany, engineer, have invented certain new and useful Improvements in Roll-Calenders, of which the following is a statement.

With the hitherto known roll calenders for paper woven fabrics and similar materials, in which the reeling attachment is driven from the one calender roll or from its countershaft, the drawback has been observed that during the calendering of the paper web the reeling attachment frequently works at an uneven tension, as the customary regulation of the latter is performed by hand and therefore depends entirely on the attention and the skill of the attendant. Both the unreeling brake and the reeling drive act on the shaft of the reeling paper roll; the brake moment must therefore be reduced with the reduction of the diameter of the paper roll and the driving moment must be increased with the increasing diameter of the roll, if the tension in the paper web shall remain uniform during the passage of the entire roll.

The present invention, now, relates to a roll calender, in which these drawbacks are obviated, because owing to the novel method of driving the reeling attachment the tension in the paper web remains fully uniform. The present invention consists essentially therein that the supporting rolls for the paper roll being reeled are driven by a calender roll driven by circumferential friction. In consequence thereof an automatic regulation of the tension in the web corresponding to the quality of the material is obtained by utilization of the brake effect of the calender rolls. By the pulling force of the reeling attachment remaining uniform also the force at the circumference of its driving roll is uniform; in other words a uniform friction and thereby a constant calendering effect is produced during the passage of the paper web.

In the accompanying drawing the new calender is shown in Figure 1 in side elevation, in Fig. 2 in front elevation. Fig. 3 is a plan of a part of the calender.

The unreeling paper roll R^1 presses against a brake drum A , which is rotated by the unreeling paper web. The paper web then travels in known manner through the

calender to the reeling attachment. The reeling attachment consists of one or two supporting rolls i^1 and i^2 journaled next each other, on which the paper web re-reels as roll R^2 . On the shaft of one or the shafts of both rolls i^1 and i^2 respectively are fitted belt-pulleys over which runs a belt s . When two supporting rolls are employed the two pulleys m and n are of a conical shape and disposed in opposite sense on their rolls. The belt s may then be shifted on the pulleys m , n so that varying speeds may be imparted to the rolls i^1 , i^2 .

The rolls i^1 , i^2 are driven by means of belt g from one of the calender rolls. As during the reeling of the paper web that tension will come into effect which is imparted to the said web by the different speeds of the two supporting rolls i^1 and i^2 , a tension in the paper is obtained which will remain uniform during the reeling, as always the same force will act on the same leverage. This method of reeling the paper web has the further advantage, that at a constant speed of the supporting rolls i^1 , i^2 the paper web will be reeled at a constant power consumption. In consequence therof a constant force will prevail also at the periphery of the driving pulley on the calender roll, so that any calender roll driven by circumferential friction may be used for driving the reeling attachment. This possibility of selecting the driving roll allows of a wide limit in regulating the frictional effect in the calender.

The difference between the circumferential speed of the two supporting rolls i^1 , i^2 , and with it the additional tension in the paper web between the two supporting rolls, which is necessary for a close reeling, may be varied according to the strength of the respective paper under treatment. If therefore the pulley driving the reeling attachment is not fitted, as it was hitherto customary, on the driving roll a or on its countershaft, but on the extended trunnion of another roll b driven by circumferential friction only, the friction between the driving roll a and the roll b favorable for the calendering is regulated in correspondence with the power required by the reeling attachment, in other words, papers with high tensile strength are reeled tighter and therefore calendered at a higher friction between the rolls a and b than papers of a lesser strength. The reeling attachment

thus affords besides the absolutely uniform tension during the calendering of the paper web, the further advantage of an automatic regulation of the friction in the calender.

The belt *g* may also drive the conical pulleys *m*, *n* directly without any second belt. In this case only guide rolls are required. In place of the one brake drum *h* also several such drums may be provided, between which the paper web travels. For securing that the drive of the rolls, and in particular of that roll which serves to drive the supporting rolls for the web to be reeled, is effected by the peripheral friction in a proper manner, it is necessary to provide that there is no excessive friction of the journals in the bearings. Therefore no split bearings but only closed bearings and bushes of one solid piece have been employed in the bearings for the rolls shown, the said sleeves, bushes and bearings being made so strong that they cannot sag. The bushes are cylindrical and are supported in the middle of their cylindrical surface by means of a transversely extending web provided in the bearing housing so as to oscillate thereon and adapt themselves in case the trunnions of the rolls should assume an inclined position when the roll might bend. As the closed bush-bearings form one solid piece, and if of sufficient thickness, afford a sufficient strength they will not bend, as it might occur

with split bearings. In consequence thereof the pressure of the journals is uniformly distributed over the whole surface 35 of the bush and there will be no uneven strain on the bearing surface and no catching of the journals, as will occur in other cases.

I claim:

1. Roll calender for paper, woven fabrics and similar materials, comprising supporting rolls for the web to be reeled, said supporting rolls being driven from one of the calender rolls which is rotated by peripheral 45 friction, any increase in friction between the calender driving roll and said calender roll, causing a corresponding automatic regulation of the tension of the reeled material.

2. Roll calender according to claim 1, in which said supporting rolls are connected by variable power transmitting means.

3. Roll calender according to claim 1, in which the bearings for the supporting rolls 55 contain a bush made in a tubular piece and oscillatingly supported on their cylindrical surface by a web of the pressure member extending transversely to said surface.

CARL SCHÜRMANN. [L.S.]
